Attorney

UNITED STATES PATENT OFFICE.

REMOUS FOERSTER, OF NOBLE, ILLINOIS.

WAGON TONGUE AND CONNECTION.

Application filed April 21, 1922. Serial No. 555,893.

To all whom it may concern:

Be it known that I, REMOUS FOERSTER, citizen of the United States, residing at Noble, in the county of Richland and State 5 of Illinois, have invented certain new and useful Improvements in Wagon Tongues and Connections, of which the following is a specification.

My invention relates to improvements in 10 wagon tongues and their connections.

An important object of the invention is to improve the construction of a wagon tongue in general, for increasing its strength, providing for a large range of adjustment, 15 and to provide adjustable means for connecting it with the hounds of the wagon.

A further object of the invention is to provide a tongue of the above mentioned character, which may be advantageously 20 used in connection with a double tree, or may be used for coupling one wagon behind another.

Other objects and advantages of the invention will be apparent during the course 25 of the following description.

In the accompanying drawings forming a part of this specification and in which like numerals are employed to designate like parts throughout the same,

30 Fig. 1 is a perspective view of a wagon tongue and associated elements, embodying my invention,

Fig. 2 is a plan view of the same,

35 Fig. 3 is a side elevation of the tongue, parts broken away and parts in section,

Fig. 4 is a perspective view of the forward hound clamp, and,

Fig. 5 is a similar view of the rear hound clamp.

40 In the drawings, wherein for the purpose of illustration is shown a preferred embodiment of my invention, the numeral 10 designates a wagon body, supported by a front axle 11, carrying front wheels 12. 45 The numeral 13 designates the front bolster and 14 are the wagon hounds, rigidly mounted between the bolster and the axle. The usual king bolt serves to pivotally connect the wagon body and bolster 13, as is well 50 known.

The numeral 15 designates a rear tongue section, which extends through and rearwardly beyond a clamp 16. This clamp includes upper and lower sections 17 and 18, 55 having flanges 19, apertured for the recep-

tion of bolts 20 and 21. These bolts serve to bind the clamp sections to the rear tongue section 15. The clamp sections 17 and 18 are apertured for receiving a pin 22, which is adapted to be passed through the double 60 tree (not shown). The pin 22 is also adapted to be passed through the apertured end of a cleat 23 secured to the clamp section 17, at 24. The pin 22, of course, passes through an opening in the tongue section 15. 65

The numeral 25 designates a pair of tongue hounds, preferably formed of metal, and provided at their forward ends with apertured knuckles 26 which are inserted between the flanges 19, and adapted to receive the bolts 20. It is thus seen that a pivotal connection is afforded between the tongue hounds and the clamp 17, which permits of lateral adjustment of the tongue hounds with respect to the wagon hounds 75 14, within limits.

The numeral 27 designates a rear tongue clamp, formed in upper and lower clamp sections 28 and 29, receiving the rear end of the tongue section 15. The sections 28 and 29 have flanges 30, which are provided with elongated slots 31. These slots receive bolts 32, which pass through apertured knuckles 33, formed upon transverse brackets 34, secured to the ends of the tongue 80 hounds 25 by bolts 35. By adjusting the brackets 34 transversely, the tongue hounds 25 may be shifted laterally, to assume positions adjacent to the wagon hounds 14. The slight lateral movement of the brackets 90 34 is taken care of by the space between the bolts 30 and the walls of the slots 31. The numeral 27' designates a bolt passing through the clamp sections 28 and 29 and the tongue section 15, as shown. 95

The numeral 36 designates a main pivot pin or element, extending horizontally and transversely through apertures 37 in the wagon hounds 14, apertures 38 in the tongue hounds 25 and an aperture 39 in the rear tongue section 15. This pin 36 pivotally connects the tongue section 15 with the wagon hounds, to permit the tongue being swung in a vertical plane.

The numeral 40 designates a forward 105 tongue section, which is shown as arranged beneath the tongue section 15, while it may be advantageously arranged above it. The tongue section 40 is adjustable longitudinally with relation to the tongue section 15, 110

and these two tongue sections have a series of spaced openings 41, to receive pins 42, carrying cotter pins 43 at their lower ends.

The numeral 44 designates a clamp, 5 rounding the tongue sections 15 and 40, and the ends of this clamp are drawn together by a bolt 45, by means of which the clamp may be securely locked to the tongue sections 15 and 40. The bolt 45 is engaged by an eye 10 bolt 46, having a retractile coil spring 47 secured thereto, the upper end of which is connected with a chain 48, as shown. This chain may detachably engage a hook 49 secured to the front end of the wagon 15 body, as shown.

From the foregoing description it is obvious that I have provided an adjustable tongue which may be applied to wagon hounds which are spaced different distances 20 apart. It will also be seen that the tongue may be used in connection with the usual double tree or may be employed as the tongue of a trailer.

It is to be understood that form of my 25 invention herewith shown and described is to be taken as a preferred example of the same, and that various changes in the size, shape, form and arrangement of parts may be resorted to without departing from the 30 spirit of my invention or the scope of the subjoined claims.

Having thus described my invention, I claim:

1. The combination with the hounds of 35 a wagon, of a tongue section extending between the wagon hounds, a forward clamp mounted upon the tongue section, said clamp embodying upper and lower sections having laterally extending flanges which are provided 40 with openings, tongue hounds arranged inwardly of the wagon hounds and converging forwardly and provided at their ends with apertured knuckles arranged between said flanges, elements passing through

the flanges and the apertured knuckles to 45 pivotally connect them, a main pivot pin passing through the hounds and tongue hounds, inwardly extending brackets rigidly secured to the rear ends of the tongue hounds and provided at their inner ends 50 with apertured knuckles, a rear clamp secured upon the tongue section and embodying upper and lower sections having laterally extending flanges, said flanges having slots 55 extending longitudinally of the flanges, and bolts passing through the slots and the apertured knuckles of said brackets, said bolts being capable of partaking of restricted lateral movement within the slots.

2. The combination with the hounds of 60 a wagon, of a tongue section extending between said hounds, a forward clamp secured to the tongue section and including upper and lower sections having laterally extending flanges, said flanges having apertures, 65 tongue hounds disposed inwardly of the wagon hounds and having their forward ends apertured, bolts passing through the apertures of the flanges and the apertures of the tongue hounds for pivotally connecting the same, a main pivot pin passing through the wagon hounds and tongue hounds rearwardly of the forward clamp, a 70 rear clamp secured to the tongue section and embodying upper and lower sections having slots extending longitudinally thereof, brackets rigidly secured to the rear ends of the tongue hounds and projecting inwardly 75 therefrom and having their inner ends apertured and arranged between the flanges of 80 the rear clamp, bolts passing through the slots of the rear clamp and through the apertures in said brackets, said bolts being movable longitudinally within said slots and also capable of partaking of slight lateral movement therein.

In testimony whereof I affix my signature.

REMOUS FOERSTER.
